X 2042 C

For Banks - Safes - Vaults - Business Houses - Dwellings - Public Buildings &c &c
 Invented by John Morgan Jr. Pittsburgh Penna.

117,444

PATENTED JUL 25 1871

UNITED STATES PATENT OFFICE.

JOHN MORGAN, JR., OF WHEELING, WEST VIRGINIA.

IMPROVEMENT IN BURGLAR-ALARMS.

Specification forming part of Letters Patent No. 117,444, dated July 25, 1871.

To all whom it may concern:

Be it known that I, JOHN MORGAN, Jr., of Wheeling, in the county of Ohio and State of West Virginia, have invented a new and Improved Burglar and Danger-Alarm, of which the following is a specification, reference being had to the annexed drawing and the letters thereon.

My invention relates to the hereinafter-described arrangement of apparatus, operated by electricity, for the purpose heretofore indicated; one part of which is located at the place to be guarded, another part at the place where the danger is to be made known, and another part connecting the two former together.

At the place to be guarded, as, for instance, the vault marked 3 in the drawing, are located the pendulum S, and its accompanying clock-work to give it motion; the elastic points T and U, against which the pendulum alternately touches as it swings backward and forward; wire 17 connecting pendulum with the ground; keys A B and C D, connected with clock-points T and U by wires 18 and 19; arm C, which presses against the keys A B and C D, and also against the door or opening. At the place where the danger is to be made known are located the relays L M and J K; battery Z, connected with relays by wires 24 and 25; local batteries A, connected with relays by wires 27 and 29; local magnets M N and F F, connected with relays by wires 26 and 30, and with local batteries by wires 28 and 31; also, the spring clock-wheel P R, which engages a similar wheel behind wheel O P, and into which the wheel M O engages. The spring-hammer S T engages in the wheel O P, and pendulum G H works in the wheel M O. The former and latter arrangements are connected the one with the other by wires 22 and 23.

The pendulum S being put into motion by the clock-work when it touches the point T, there is a complete electrical circuit made, thus: from ground in or near vault, through wire 17, pendulum S, point T, wire 18, key A B, wire 22, relay J K, wire 25, and battery Z. This being the case the relay J K is closed, which brings armature 36 in, thereby closing local magnet F F, which draws the pendulum G H to it, which causes the hammer

R S to strike gong V W. As soon as pendulum swings away from point T the circuit is broken and armature 36 flies back, destroying circuit in local F F, and then pendulum G H swings away, to be drawn to local M N as soon as the other circuit is made by the pendulum S touching point U. The pendulum G H, in this arrangement, vibrates in accord with pendulum S. If either of the wires 22 and 23 are broken it will stop the beat of gong V W; if both are broken, or door of vault is opened, makes the pendulum G H hang perpendicular and still, and this allows the spring-wheel R to run off and rapidly ring gong V W; either or both of the wires 22 and 23 being grounded outside of the vault, it will catch and hold the pendulum G H to one side, thereby stopping the beat of hammer S upon gong V W.

If any one were well enough acquainted with this arrangement to prepare a clock with the same beat, to use it would still give alarm, unless he also caught the same swinging time as the direction of pendulum S; but this can be overcome by changing every day the beat and direction of the pendulum S.

It is evident that the wires, after leaving pendulum S, can be run all around the sides of the vault, so as to make it impossible to disturb it in any place without interfering with them. It is also evident that this arrangement can be so connected with a building as to give notice of fire.

Having thus described the relative arrangement of the apparatus which compose my invention, and the operation of the same for the object intended, I claim as my invention, a desire to secure by Letters Patent, the following:

The arrangement, herein shown, of the pendulum S, connected by wire 17 to the ground, clock-points T and U, wires 18 and 19, keys A B and C D, arm C, wires 22 and 23, relays L M and J K, battery Z, wires 24 and 25, magnets F F and M N, wires 26 and 30, local batteries A, wires 28 and 31, and pendulum G H, substantially as and for the purpose herein set forth.

JNO. MORGAN, JR.
